UNITED STATES PATENT OFFICE.

HENRY K. PORTER, OF BOSTON, MASSACHUSETTS.

DESIGN FOR AN AXLE-YOKE.

SPECIFICATION forming part of Design No. 16,185, dated July 28, 1885.

Application filed May 2, 1885. Term of patent 14 years.

To all whom it may concern:

Be it known that I, HENRY K. PORTER, of Boston, in the county of Suffolk and State of Massachusetts, have invented a new and useful Design for Axle-Yokes, which will, in connection with the accompanying drawings, be hereinafter fully described, and specifically defined in the appended claim.

The invention consists in a new design for the article of carriage hardware known to the trade as "axle-yokes," "clip-yokes," and "axle-clip ties;" and it consists in the peculiar configuration of the ends of the yoke, as shown in the accompanying drawings, in which—

Figure 1 is a perspective view of an axle-yoke embodying my invention. Fig. 2 is a top plan view thereof. Fig. 3 is a reverse perspective view, and Fig. 4 is a top plan view thereof, these several views being deemed necessary to fully illustrate my design.

In said figures, *a* is the upper side or plane of the yoke, that portion thereof which is included between shoulders *d* representing the portion which is covered by the axle, while that portion at each end between said shoulders *d* and the nearest end or plane *g* constitutes the finished portion. The ends of the plane *a* are bounded by said shoulder and by line *e*, which extends from the shoulder toward the end parallel with sides *b* till its nearest approach to clip-holes *c*, when it constitutes a semicircle of slightly greater diameter than hole *c*, and parallel with the line thereof.

Side planes, *b*, are bounded at the ends by said shoulders and line *f*, which latter extends from the shoulder to the lower point of the angle at the intersection of side planes, *b*, and ends *g*, while the end of the yoke may constitute a limited plane, *g*, whose lower bound is line *j* and upper bound is curved line *h*, as shown in Figs. 1 and 2; or the end may be brought by a curve from the lower end line, *j*, merging in lines *f* and *e*, as shown in Figs. 3 and 4, in which case the area *i* would be bounded by shoulders *d* and lines *c*, *f*, and *j*.

I am aware that heretofore axle-yokes have been designed and made in which the upper plane was bounded by shoulders *d* and line *e*; but the side planes, *b*, were bounded by said shoulders *d*, which extended to the bottom of sides *b*, and I am aware that in axle-yokes end *g* has been bounded at its upper limit by curved line *h*, but not when the other boundaries of area *i* were shoulders *d* and lines *c* and *f*.

I claim—

The design for axle-yokes, consisting in the configuration of the ends thereof brought from right angles at the bottom by convex side lines, *f*, to convex line *e*, and angular shoulders *d*, as shown in the accompanying illustrations.

HENRY K. PORTER.
